(57) **CLAIM**

The ornamental design for an office chair, as shown and described.

DESCRIPTION

FIG. 1 is a front, right, top perspective view of an office chair, showing my new design;

FIG. 2 is a rear, left, bottom perspective view thereof;

FIG. 3 is a front elevational view thereof;

FIG. 4 is a rear elevational view thereof;

FIG. 5 is a left side view of the enlarged scale thereof;

FIG. 6 is a right side view of the enlarged scale thereof;

FIG. 7 is a top plan view of the enlarged scale thereof; and,

FIG. 8 is a bottom plan view of the enlarged scale thereof. The dashed broken lines in the figures are for the purposes of illustrating portions of the office chair and form no part of the claimed design.

1 Claim, 8 Drawing Sheets
